UNITED STATES PATENT OFFICE.

WALTER E. McCREARY, OF ALTOONA, PENNSYLVANIA.

AUTOMOBILE MAGNETO CONTACT.

1,312,794.

Specification of Letters Patent. Patented Aug. 12, 1919.

Application filed December 23, 1916. Serial No. 138,639.

To all whom it may concern:

Be it known that I, WALTER E. McCREARY, a citizen of the United States, residing at Altoona, in the county of Blair and State of Pennsylvania, have invented certain new and useful Improvements in Automobile Magneto Contacts, of which the following is a specification.

This invention relates to electrical contact devices and more particularly has special reference to a magneto contact for the ignition system of Ford automobiles.

Primarily, the object of the invention is to provide improved means for collecting the current generated by the magneto which is built in the fly-wheel and from which a low tension alternating current flows through the primary windings of the coil, usually positioned on the dash, to the commutator, which is located in front of the engine, and thence back through the frame of the car to the magneto, to complete the primary circuit. Current flowing through the primary windings of the coils induces a high tension current in the secondary windings of the coils, from which it flows to the spark plugs as each wire's circuit is completed by the commutator.

Another object of this invention is to further increase the efficiency of the ignition system of the Ford car by providing a magneto contact device that is not susceptible of being rendered inoperative by particles of brake bands, fiber and oil being caught between the magneto contact point and the stationary windings on the magneto.

A further object of this device is to provide a contact point for the magneto which is so constructed that when the same is screwed into position in the fly-wheel casing, the plate on the magneto coil to which one end of the magneto coil is secured is not disturbed or dislocated.

A still further object of this device is to provide a simple, efficient and practical method of renewing the magneto contact point, since as they are now made, it is an arduous task to remove and replace one.

With the above and other objects in view which will more readily appear as the nature of the invention is better understood, the same consists in the novel construction, combination and arrangement of parts hereinafter more fully described, illustrated and claimed.

It will be quite readily understood by

those skilled in the art to which this invention belongs that the same is susceptible of changes in the construction and manufacture without departing from the spirit or scope of the invention, but a preferred and practical embodiment of the invention is illustrated in the accompanying drawings, in which—

Figure 1 shows a partial side elevation of the Ford motor with my improved magneto plug positioned therein.

Fig. 2 is a sectional view taken on the line 2—2 of Fig. 1, illustrating the construction of the magneto as well as the position of the improved magneto contact.

Fig. 3 shows a sectional view of the improved magneto contact, and also shows its operative relation with the stationary part of the magneto.

Fig. 4 shows an elevational view of the improved magneto contact.

Fig. 5 shows the front and side views of the magneto contact plate which is adapted to be secured to the magneto case, by suitable screws or other means.

Similar reference characters designate corresponding parts throughout the several figures of the drawings.

In applying this invention to the Ford automobile engine, no change is contemplated in the motor or motor mechanism which may be designated by the numeral 10, including the engine E, and the usual transmission cover C.

The Ford magneto, which generates the ignition current together with the lighting current is constructed as an integral part of the motor, and consists primarily of two sections, one of which is attached to and rotates with the fly-wheel while the other is securely fastened to the motor or transmission case. That portion of the magneto which revolves with the fly-wheel 11 consists of a series of sixteen magnets 12, so positioned on the fly-wheel 11 that the magnet poles of opposite kind are adjacent and held in place by a common clamp.

Since these various magnets revolve at the same speed as the motor, these magnets pass the stationary coils 13 and create therein an alternating low tension current, which is carried from these coils to the magnet contact designated in its entirety by the numeral 14. The manner and means of collecting this current has been one source of ignition trouble with this type of car for

some time, due principally to particles of brake band fiber being caught between the coil terminal plate 15 and the magneto contact point 16.

- 5 The present invention provides means whereby the particles of brake band fiber will not have any effect upon the contact point with the coil terminal, and to this end, the invention contemplates the removal 10 of the present pointed contact piece and provides in its stead a left hand wound helical spring 17, the plate engaging end, of which is ground so as to rest firmly on the plate. Thus, pieces of brake band fiber 15 carried up by the fly-wheel will, when caught, by the coils of the spring, be deflected away from the magnets and because of its persisting resiliency, the spring will not be disengaged from the plate 15 with the 20 result that the current flow is uninterrupted in the primary coils.

In the manufacture of this magneto contact, I take a cold drawn brass rod 18 and upset or slightly increase the diameter as at 25 19, below which I reduce the diameter and draw the wire out to such a length that when coiled the helical spring 17 is the result.

I prefer to coil this spring left handed, which eliminates any tendency of the end of 30 the coil from damaging the coil plate 15 to which one terminal of the magneto coil is secured, while the opposite terminal end thereof is grounded on the frame.

Having thus constructed the helical spring 35 from the rod 18, I further thread the top 20 of the rod after which I pass the rod through a properly constructed conical insulating sleeve 21, which has a socket at its lower end to snugly receive the enlarged 40 abutment portion 19 of the rod 18 such that when the nuts 22 are drawn down the rod will not pull through the tube 21. Around the conical portion of the tube 21, I provide

a separate insulating body or casing 23, which is adapted to be clamped between a 45 top washer 24 and a hexagonal wrench engaging member 25.

In applying this magneto contact, I prefer to use an adapter plate 26, which is properly threaded to receive the threaded neck 27 50 of the member 25 together with properly located screw holes 28 through which pass suitable screws 29, for securing the plate to the transmission case 30.

This construction obviates the difficulty 55 that is likely to arise from the screws becoming loose in the transmission case through numerous removals and replacements which will obviously occur with continued usage. Furthermore, the integral 60 construction of this improved magneto contact, will necessarily obviate the loss of any current between the magneto and the coils, thus improving the ignition system as well as to provide a more dependable part of the 65 Ford ignition system.

I claim:

1. A magneto contact device of the class described, consisting of a holding member having an interior shoulder; and an electrical 70 conductor rod having an abutment portion for engaging with said shoulder and a left-coiled helical spring contact terminal.

2. A magneto contact device of the class described, consisting of a holding member 75 having an interior shoulder and an electrical conductor rod having formed integrally therewith an enlarged stop portion to engage said shoulder and a left-coiled helical spring contact.

In testimony whereof I affix my signature in the presence of two witnesses.

WALTER E. McCREARY
